UNITED STATES PATENT OFFICE.

ELMER J. ZELT, OF FORT WAYNE, INDIANA, ASSIGNOR TO GENERAL ELECTRIC COMPANY, A CORPORATION OF NEW YORK.

ELECTRIC SIGNAL LAMP.

Application filed July 20, 1925. Serial No. 44,695.

My invention relates to electric signal lamps and its general object is to provide an improved arrangement of lamp and mounting for use where the support for the 5 lamp is subject to severe shock and vibration. The invention is particularly applicable in connection with electric signal lamps for use on railway switches where the shock and vibration from passing trains are very great. 10 A signal lamp is commonly mounted with part of the railway switch structure on the extended ends of two or three of the ties which support the track and the vibration from passing trains is extremely destructive 15 to the lamp filament unless some means is provided to absorb the vibration before reaching the filament. It is desirable that the lamp be designed for low voltage as the filament is less fragile than in a high voltage 20 lamp and in accordance with the invention a transformer is provided to reduce the voltage of the supply circuit, the mass of the transformer being utilized to absorb shocks and vibration and reduce their destructive 25 effects on the lamp filament.

Other objects and advantages will appear from the following description taken in connection with the accompanying drawing in which Figure 1 is a side view of a lamp constructed in accordance with the invention, part of the casing being broken away to reveal details of structure, Figs. 2 and 3 are side views of the resiliently mounted transformer and lamp socket and Figs. 4 and 5 are views of details of the structure.

Like reference characters refer to similar parts in the different figures of the drawing.

In the particular lamp structure shown in the drawing, an outside protective casing 10 is provided in the usual way with lenses 11 which may be of different colors to indicate the position of a switch as the lamp is rotated with the switch operating lever. The casing 10 is mounted on a supporting base 12 which is assumed to be part of some structure such as a railway switch which is subject to excessive shock and vibration.

The casing 10 is formed with a lower compartment for a transformer 13 which is 50 resiliently supported by a helical spring 14.

Two plates or disks 15 are secured to the two end turns respectively of the spring 14 by prongs 16 formed integrally with the plates. The transformer is secured to the upper plate 15 and hangs in the space surrounded 55 by the spring 14 and between the two plates 15. The lower plate 15 is secured to the bottom of the casing 10 by screws or bolts 17 which engage the plate through slots 18 in the plate. One end of each slot 18 is 60 enlarged to pass over the head of the bolt, after which the plate may be rotated slightly to move the narrow end of the slot under the head of the bolt which is then tightened. The edges of each slot 18 at the junction 65 of its narrow and enlarged portions are turned up to form raised stops 19 so that if the bolts become loosened by vibration the narrow portions of the slots will be retained in position under the bolt heads and the 70 plate cannot be entirely released.

A plate 20 of insulating material carrying a lamp socket 21 is mounted by short posts on the upper plate 15. The parts which have been described are of such height 75 that a lamp 22 in the lamp socket 21 is properly positioned behind the lenses 11. The high voltage leads 23 from the transformer are brought out through a suitable opening 80 in the casing 10 for connection to an outside source of current and the low voltage leads 24 are connected to the lamp socket 21 to supply current for the lamp 22.

The invention provides a compact structure which is particularly effective in preventing the transmission of shock and vibration from the lamp support to the lamp filament and consequent rapid destruction of the filament.

What I claim as new and desire to secure 85 by Letters Patent of the United States, is,—

1. A signal lamp including a base, a rigidly connected transformer and lamp, and a resilient member mounted on said base and supporting said transformer and lamp.

2. A signal lamp including a base, a rigidly connected transformer and lamp, and two members spaced apart by a resilient spring, one of said members being mounted 100

on said base and the other of said members positioned in the space within said helical carrying said transformer and lamp.

3. A signal lamp including a base, two spaced plates, a helical spring connecting said plates, one of said plates being secured to said base, a transformer secured to and supported by the other of said plates and positioned in the space within said helical spring and between said plates, and a lamp secured to said transformer supporting 10 plate.

In witness whereof, I have hereunto set my hand this 16th day of July, 1925.

ELMER J. ZELT.
